INVENTOR

John C. Wilson

United States Patent Office.

JOHN C. WILSON, OF NEW YORK, N. Y., ASSIGNOR TO RICHARD CAMPBELL, OF SAME PLACE.

Design No. 3,999, dated April 26, 1870.

DESIGN FOR A SKEWER-CUSHION.

The Schedule referred to in these Letters Patent and making part of the same.

To all whom it may concern:

Be it known that I, JOHN C. WILSON, of the city, county, and State of New York, have invented a new and original Design for Skewer-Cushion for Stable Purposes; and I do hereby declare that the following is a full, clear, and exact description thereof, which will enable others skilled in the art to make and use the same, reference being had to the accompanying drawing forming part of this specification.

The figure represents my improved skewer-cushion.

My invention has for its object to furnish an improved design for a cushion for holding skewers, pins, &c., for stable uses, which is designed to be hung up in stables, stable-offices, &c., and which shall serve at the same time as an advertising card for the maker, and

It consists in the design for a cushion herein shown and set forth.

A is the frame of the cushion, which is cast in the form shown in the figure, and with a scroll, B, upon its upper part, to receive the name of the maker.

C is the cushion, in which the skewers and pins are to be stuck.

I claim as my invention—

The design for a skewer-cushion herein shown and described.

The above specification of my invention signed by me this 6th day of April, 1870.

JOHN C. WILSON.
